UNITED STATES PATENT OFFICE.

VINCENT J. WHITNEY, OF SAN FRANCISCO, CALIFORNIA.

WINDOW-SASH STOP.

Application filed October 13, 1924. Serial No. 743,356.

It is one object of my invention to provide a stop mechanism whereby the extent to which a pivoted window sash may be opened may be positively limited.

5 It is another object to provide a device of the character indicated so positioned and connected to the interior of the sash as to render it impossible to disconnect it from the sash when opened to any degree.

10 It is still another object to provide a stop mechanism of the character indicated for that type of pivoted sash disclosed in my co-pending application for window support, filed Dec. 1, 1922, Serial No. 604,379, in which 15 the sash is both pivotally and slidably mounted in the window frame and fitted with means for preventing movement relative to the frame unless manual force is applied thereto.

20 It is also an object to provide a device of the character indicated that will be simple in form and construction, economical to manufacture, and highly efficient in its practical application.

25 In the drawing:

Figure 1 is a plan view of a device embodying my invention operatively mounted with relation to a sash, a portion of the sash and window frame being shown in section, and 30 the sash being in a closed position.

Figure 2 is a view similar to that shown in Figure 1 but with the sash opened a distance.

Figure 3 is a side elevation of the device 35 embodying my invention in the position shown in Figure 1.

Referring more particularly to the drawing, I show at 1 a window stool, at 2 the window frame, and at 3 a portion of a window 40 sash mounted therein.

The sash 3 is pivotally mounted on a shoe 4 sliding in a track 5 and frictionally held in any given position by a spring 6 inserted between shoe 4 and track 5. An arm 7 is 45 pivotally connected to the sash 3 and the track 5 as shown.

At 8 is shown a bracket mounted on the sash 3 and provided with a knob 9, the handle end of the bracket lying substantially parallel with the sash 3. It is obvious that by 50 pushing outwardly upon bracket 8 the shoe 4 will slide in track 5 and the sash 3 can be made to assume any desired position.

While this construction will hold the sash 55 in any desired position against wind pressure the sash may be readily swung clear open

at right angles to its normal closed position by anyone on the outside who may thereby gain an entrance to the building through the window.

60

To remedy this condition I provide a hook member 10 pivotally mounted on the stool 1 as at 11, and engaging the knob 9. This hook member is elongated as shown, its length being determined by the extent to 65 which it is desired to limit the opening of the sash with the pivotal point of the hook located in a given position.

This hook may also be provided with additional recesses as shown at 12, forming in 70 effect a shorter hook by means of which the opening of the sash may be further limited if so desired.

In the present disclosure the hook 10 is 75 normally held in engagement with the knob 9 by means of a spring 13 mounted to bear against its rear edge as shown so that it cannot become accidentally disengaged from the knob 9 even when the sash is entirely closed, and it is obviously impossible to disengage 80 the knob and hook when the sash is opened a distance. However, by pressing the hook backwardly against the spring when the sash is closed the knob may become disengaged 85 therefrom and the sash opened to any extent.

The hook 10 swings in a plane parallel with the stool 1 and bracket 8 and is so formed and positioned that no portion extends beyond the edge of stool 1 so that it does not disfigure the stool or interfere with 90 curtains.

While it is desirable to protect the invention broadly it is particularly desired to protect the combination of the sash mounting shown, (the pivotally and slidably 95 mounted sash) with the sash bracket and pivoted hook. In this combination the bracket end lies substantially parallel with sash 3 so that when sash 3 is opened a distance and its pivoted end slides along track 5 knob 9 travels on a flatter arc than would be the case if the sash were pivoted on hinges in the usual manner. This being the case the pull on hook 10 varies 100 little from a straight line passing through point 11 parallel to the normal closed position of the sash. Consequently the said point 11 may be located adjacent the casing 14 and well out of sight through the window without permitting the hook 10 to 105 contact with the edge 15 of said casing.

110 It may now be seen that I have provided

a device that will permit opening of the sash for ventilation and yet effectively prevent anyone from effecting an entrance through the window opening.

5 It is to be understood, of course, that while I have herein shown and described one specific embodiment of my invention, changes in form, proportions and method of operation may be made within the scope 10 of the appended claims.

I claim:—

1. The combination with a window frame, a sash pivotally and slidably mounted therein, and an operating bracket mounted on 15 said sash, of means mounted on said frame and engaging said bracket and limiting the movement thereof.
2. The combination with a window frame, a sash pivotally and slidably mounted there- 20 in, and friction means for maintaining said sash in any given position in said frame, of an operating bracket mounted on said sash, and means mounted on said frame and en- 25 gaging said bracket and limiting the move- ment thereof.
3. The combination with a window frame, a sash pivotally and slidably mounted there- in, and an operating bracket mounted on

said sash and extending inwardly and thence laterally a distance substantially 30 parallel with the plane of the window, of a hook pivotally mounted on said frame and engaging said bracket and allowing a limited movement thereof.

4. The combination with a window frame 35 and a sash pivotally mounted therein, an operating bracket mounted upon said sash, a stop mounted upon said frame to engage said bracket, and means for normally urging said stop into engagement with said 40 stop engaging means.

5. The combination with a window frame, and a sash movably mounted therein and having an operating bracket mounted on 45 said sash, of a stop mounted on the window frame and engaging said bracket and permitting a limited movement thereof.

6. The combination with a window frame and a sash movably mounted therein, of an operating bracket mounted upon said sash, a 50 stop mounted upon said frame to engage said bracket, and means for normally urging said stop into engagement with said stop engaging means.

VINCENT J. WHITNEY.
